UNITED STATES PATENT OFFICE.

AVILA THOMAS, OF DETROIT, MICHIGAN.

REINFORCING-BAR FOR CONCRETE STRUCTURES.

No. 905,480.

Specification of Letters Patent.

Patented Dec. 1, 1908.

Application filed September 28, 1907. Serial No. 394,881.

To all whom it may concern:

Be it known that I, AVILA THOMAS, a citizen of the United States, residing at Detroit, in the county of Wayne, State of Michigan, have invented certain new and useful Improvements in Reinforcing - Bars for Concrete Structures; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates generally to reinforced concrete structures, and particularly to reinforcing members for cementitious and analogous bodies, and consists in the construction and arrangement of parts herein-
after more fully set forth and claimed.

The primary object of the invention is to provide simple and efficient means whereby a cementitious mass or body capable of resisting high compression, but naturally deficient in tensile-strength may be so reinforced as to enable it to successfully resist all the tensile and shearing strains to which it may be subjected.

The invention further contemplates the construction of a reinforcing bar for concrete structures consisting of a main tension member and minor shear members, said parts being so constructed as to enable the shear members to be associated with the tension member at any desired angle thereto and at any desired point and securely attached to said bar.

The invention further contemplates means for effecting a connection between the tension member and the oblique shear members of such a character as to enable the shear members to be readily associated with the tension member and when properly positioned securely locked thereto.

The above objects are attained by the structure illustrated in the accompanying drawings, in which:—

Figure 1 is a longitudinal sectional view through a concrete beam or girder reinforced with my improved bar. Fig. 2 is a plan view of the tension member with the diagonal shear members omitted. Fig. 3 is a fragmentary view in perspective of a portion

of the tension member. Fig. 4 is an elevation of a portion of the tension member and one of the shear members, showing the manner of associating said members and by dotted lines the relative position thereof when associated. Fig. 5 is a fragmentary view in perspective of a portion of the completed bar comprising the tension member and shear members mounted thereon in readiness for incorporation in a concrete beam or other structure. Fig. 6 is an elevation of a portion of one end of the tension member, showing one of the shear members locked thereon. Fig. 7 is a perspective view of one of the shear members shaped for association with the tension member. Fig. 8 is a transverse section through a beam containing a modified form of reinforcement, wherein is employed three longitudinally extending tension members connected by the shear members. Fig. 9 is a side elevation thereof. Fig. 10 is a perspective view of the shear member employed in the structure shown in Figs. 8 and 9. Fig. 11 is an elevation of a reinforcing bar whose tension members are mounted thereon to cross one another in a manner to form a latticed beam or column. Fig. 12 is a plan view of the tension member employed in the construction shown in Fig. 11. Fig. 13 is a plan view of one end of the structure shown in Fig. 8. Fig. 14 is an inverted plan view of the structure shown in Fig. 6, the end portions of the tension member being broken away.

In the ordinary reinforcement of concrete or cementitious bodies, such as beams, columns, girders, and floors, it is desirable to employ a reinforcing bar which shall be free from excessive weight, and yet possess the requisite tensile-strength, and to associate with said tension member shear members of a character to establish a firm bond between the cementitious body and the tension member and so positioned and lying in such planes as to traverse the probable line of fracture nearly at right angles thereto, providing at the same time for a proper distribution of the shear members in the concrete structure as to properly counteract the shearing stresses. Such a bar or structure is shown in the drawings forming a part of this specification, wherein 1 design-

nates the tension member which is a metal bar T-shape in cross section, thereby affording the lateral flanges 2. To enable the attachment of the shear members to the tension member, the flanges 2 are provided with a plurality of opposed slits 3 at an angle of 45° to the axis of the tension member, one of the marginal portions of each of the slits by the operation of cutting being raised or curved upwardly, as shown at 4, thereby opening the slits so as to allow the tension members to enter freely therein.

The tension members as will be seen on referring to Fig. 7 are formed of flat sheet metal of the requisite gage and are first cut in straight lengths after which their end portions 5 are bent upwardly on a line crossing the body portion 6 of the shear member at an angle of about 45°, said end portions standing at right angles to the body of the shear member and parallel to each other with their inner faces in substantially right angle planes. The length of the body portion 6 of the shear members is equal to the diameter of the central portion of the tension member, and the shape of the shear members is such as to enable their end portions 5 to be entered in the diagonal slits 3 from the under side of the tension member, while the angle at which the end portions of the shear members are bent causes said end portions when introduced in the slits of the tension member to project obliquely to the tension member when the body portion 6 of the shear members is caused to lie flatly against the under face of the tension member, as shown in Figs. 5, 6 and 14, the angle at which the end portions of the shear members project from the tension member being at about 45° to a perpendicular. After the shear members shall have been placed in the slits of the flanges of the tension member with the body portions of the shear members crossing the under face thereof, the tension members are securely locked to the shear member by driving or forcing the upwardly turned margins 4 of the slits downwardly against the inclined sides of the shear members in a plane with the major portion of the flanges 2, as clearly shown in Figs. 5 and 6, thereby forming an abutting shoulder which serves to resist any longitudinal thrust upon the shear members in the direction of the tension member and locking the shear members firmly to the tension member.

In the making of commercial bars, the inclined slits for the shear members in the flanges of the tension member will be located at the probable point of occurrence of the shearing stress in the beam in which the bar may be placed. Should it be necessary to provide for extraordinary resistance against shearing stresses, the slits in the flanges of the tension member may be so located that

the shear members will be distributed in the concrete body in a manner to resist or counteract any predetermined shearing stresses to which the beam or concrete body may be subjected.

By making the slits in the flanges of the tension member diagonal, as shown, the shear members when placed therein are caused to assume an incline at an angle of substantially 45° with respect to the tension member, a position in which they are best calculated to traverse the probable line of fracture. It will also be noted that the oblique form of the slits enables the employment of shear members of a width greater than that of the lateral flanges 2; at the same time keeping the shear members within the plane of the tension member, affording the use of shear members of greater transverse area without increasing the bulk of the reinforcing bar or adding to its transverse diameter, while the angle at which the shear members stand in the concrete body renders them stiff as against lateral movement and capable of adding to the compression resisting strength of the beam. It will further be noted that the body portion 6 of the shear members being embedded in the concrete is held firmly to the under face of the tension member, obviating the possibility of any displacement of said parts. Where it is desired to produce the lattice effect in the reinforcing structure, the lateral flanges of the tension member are slotted on opposite sides so that the angle of the slits in pairs will stand in opposite directions, as shown in Fig. 12, permitting the incorporation of the shear members into the structure in a manner to cause their free ends to cross or lap, as clearly shown in Fig. 11, the arrangement being such as to cause the shear members in each pair to stand in opposite directions.

Where it is desired to supply a concrete bar or similar structure with a tensile strength greater than that afforded by the bar illustrated in Figs. 1 to 5, such additional tensile strength may be supplied by employing the structure shown in Figs. 8, 9, 10 and 13, wherein two angle iron tension members 7 with diagonal slits 8 in the lateral flanges 9 thereof and a central tension member 10 located equidistant between the central tension members 7, are bound together by the shear member whose body portion 6 is sufficiently long to span between the angle iron tension members 7 and which is provided with an eye 11 formed by slitting the body portion longitudinally at its center and curving the parts divided by said slits in opposite directions, as clearly shown in Fig. 10, said eye so formed receiving the central tension member 10 which passes therethrough while the upwardly extending

end portions 5 of the shear members project obliquely from the slots 3 and are secured therein in the same manner as described with respect to the tension member 1. By this arrangement the required tensile strength is supplied and the proper resistance to the shearing stress is afforded while all of the parts of the reinforcing structure are firmly bound together and are caused to maintain their proper relative position in the enveloping concrete body; the arrangement affording the same facility of distributing the shear members in the concrete as is afforded by the structure illustrated in Figs. 1 to 5.

Having thus fully set forth my invention, what I claim as new and desire to secure by Letters Patent, is:—

1. A reinforcement for concrete comprising a tension member having a flat under side and a lateral flange, said flange having a diagonal slit therein, a relatively thin and flat shear member having an end portion lying in said diagonal slit and projecting at an angle therefrom, and a flat body portion 25 lying closely against the under side of said tension member.

2. A reinforcement for concrete comprising a tension member having a lateral flange, said flange having a diagonal slit therein, a shear member of relatively thin flat material, having an end portion bent at right angles to the body portion on a line substantially at an angle of 45° to the transverse axis of said member, said end portion 35 of the shear member passing through and lying in said slit and the flat body portion of said shear member engaging the under side of said tension member.

3. A reinforcement for concrete, comprising a tension member having lateral flanges provided with opposed diagonal slits, a shear member of flat material having end portions bent at right angles to the body portion on a line substantially at an angle of 45° to the 45 transverse axis of said shear member, said end portions of the shear member passing through and lying in the opposed slits in said flanges, the flat body portion of the shear member between said end portions 50 crossing the under face of the tension member and lying closely thereagainst.

4. A reinforcement for concrete, comprising a tension member having a lateral flange, provided with a diagonal slit, a shear member of flat material having an end portion bent at an angle to the body portion thereof, said end portion of the shear member passing through and lying in said slit, the flat body portion of the shear member crossing 60 and lying closely against the under face of the tension member and the marginal portion of the slit forcibly engaging the flat face of the shear member to lock it therein.

5. A reinforcement for concrete, comprising

ing a tension member having a lateral flange 65 provided with a narrow slit therein, the material of said flange along the longitudinal margin of said slit lying parallel with the slit opening being bent or turned outwardly, a relatively thin, flat shear member 70 of greater width than thickness having a vertically extending portion lying in said slit and a horizontally extending portion crossing the under side of the tension member, the outwardly turned marginal portion 75 of the slit being movable into forcible engagement with the flat side of the shear member across the entire width thereof to lock the shear member in said slit.

6. A reinforcement for concrete, comprising a shear member having a lateral flange provided with a plurality of diagonal slits extending alternately in opposite directions, flat shear members located in said diagonal slits so as to cross each other, said shear 85 members being locked in said diagonal slits.

7. A reinforcement for concrete, comprising parallel tension members each of which is provided with a lateral flange having a diagonal slit therein, a third tension member 90 interposed between said flanged members, a flat shear member crossing between the flanged tension members and engaging the central tension member, the end portions of the shear member engaging in the diagonal slits of said flanged tension members.

8. A reinforcement for concrete, comprising a tension member having laterally projecting flanges, said flanges being provided with straight, narrow slits extending therethrough and diagonally disposed with respect to the axis of the tension member, a flat shear member of much greater width than thickness, having its end portions bent at right angles to the body portion thereof 105 and turned to stand obliquely with respect to the transverse axis of said shear member, said bent and turned portions of the shear member passing through the diagonal slits in said flanges and the flat body portion of 110 the shear member intermediate its ends crossing and lying closely against the under face of the tension member.

9. A reinforcement for concrete comprising parallel tension members each of which 115 is provided with a lateral flange having narrow slits therein, a third tension member interposed between said flanged members, a relatively thin, flat shear member crossing between the flanged tension members and having an eye therein through which passes 120 the central tension member, the ends of the shear members engaging in the slits of the flanged tension members and projecting therefrom.

10. A reinforcement for concrete, comprising parallel tension members spaced from each other and each provided with a lateral

flange having narrow slits therein, a plurality of relatively thin, flat shear members crossing between the flanged tension members and lying against the under faces thereof, the ends of said shear members being bent upwardly at substantially right angles to the body portion thereof and said upwardly bent end portions lying in the slits

of the lateral flanges of the tension members and projecting therefrom.

In testimony whereof, I sign this specification in the presence of two witnesses.

AVILA THOMAS.
